UNITED STATES PATENT OFFICE.

JOB HUTCHINSON, OF BROOKLYN, NEW YORK.

CHANGEABLE INDICATOR.

1,285,716.

Specification of Letters Patent.

Patented Nov. 26, 1918.

Original application filed May 15, 1916, Serial No. 97,615. Divided and this application filed December 4, 1917. Serial No. 205,352.

To all whom it may concern:

Be it known that I, Job HUTCHINSON, a citizen of the United States, residing at Brooklyn, in the county of Kings and State 5 of New York, have invented new and useful Improvements in Changeable Indicators, of which the following is a specification.

My invention relates to changeable indicators, in general, and more particularly to train departure indicators for railway depots. The present application is drawn to the specific structure of the indicator and provides means for indicating the time of 10 departure and list of stations, and particular means including the specific form and operation of the device used in effecting the changes in the reading of the indicator.

The objects of the invention are to provide 20 a self contained apparatus which will indicate the desired data from any direction in which the indicator may be used, to improve the simplicity of operation and reduce the initial cost of manufacture and make possible the easy repair of the instrument.

In the construction of the apparatus embodying this invention I provide a frame of sufficient height to carry the track number and time data the proper distance above the 30 floor level, and all operating connections are arranged near the base of the frame where they may be readily reached and manipulated by a person standing on the floor.

35 The invention consists in the novel combination of parts and features of construction hereinafter described and claimed, and shown in the accompanying drawings, in which

40 Figure 1 is a front view of the indicator, showing the roll cabinets at the base of the frame for the reception of rolls of display curtains, the location of the track number data at the top of the frame, and in the portion broken away a view of the structure for 45 operating the time indication data and lifting the display curtain which lists the stations.

Fig. 2 is a side view of the structure 50 shown in Fig. 1 showing in dotted lines and in the portion broken away the relative location of the parts. This view shows the design of the upper part of the structure provided with a forwardly extending dis- 55 play projection so that the track numbers may be seen at either side of the structure.

Fig. 3 is a view showing the position of the parts for moving the time card rack and lifting the display curtain which shows the stations.

60

Fig. 4 is a view showing in section the structure of the time card rack, the studs for fastening the device to the stud blocks of the carrying chain being shown in position.

65

Fig. 5 represents one end of the display curtain and the eyelets for the reception of the hooks carried by the elevating chain.

Like numerals refer to like parts in the drawings.

70

Referring to Fig. 1 of the drawing the structure shown provides a framework of wood or metal or a combination of both. The lightness of the operating mechanism makes it possible to use a framework of 75 wood which may be covered with metal sheeting for the sake of appearance. The lower part of the structure provides a number of doors 1 which are mounted on pivot hinges. The hinges are preferably located 80 about a third of the way from the bottom of the door so that the weight of the door and its racks will be properly balanced. On the inner side of the door are a plurality of racks 2 for the reception of the rollers 3 85 each of which carry a flexible curtain 3a bearing the data for the stations, these rolls being conveniently stored in the base of the indicator structure. The balance of the door may be so arranged that the weight of the 90 rolls will automatically close the door and thus dispense with any fastening devices.

The indicating apparatus and moving parts of the indicator are carried in the upper portion of the structure and suitable 95 crank attachments are provided at a point convenient to the operator for adjusting the mechanism. Near the base of the moving parts and above the storage drawers 1 are bearing members 4 and at the top of the 100 structure are additional bearing members. The bearing members 4 are fastened to the side walls of the supporting frame and are of standard size so that the parts may be interchanged. Extending horizontally between the bearing members 4 at the bottom is a shaft 5 provided with the gears 6 and 6a. The operation of the stub shaft 7 or the stub shaft 7a by the removable crank 8 turns a gear 9 or gear 9a which in turn mesh with 110 and turn the gears 6 and 6a respectively. Spaced apart on the shaft 5 are the sprocket

95

100

105

110

members 10 which are driven by the shaft 5. At the top of the structure in the bearing blocks previously mentioned is a similar shaft carrying similar sprockets but this 5 upper shaft has no driving connections and the sprockets act merely to carry the chains 11 which are driven by the lower sprockets 10. The chains 11 when operated by the turning of either stub shaft 7 or 7^a move 10 up and down in their travel and never progress beyond the height of the sprocket structure. This movement is practically to be compared to reciprocating motion as differentiated from a continuous turning movement. The chains 11 carry the hook members 12, Fig. 5, which are adapted to engage 15 with the rod 13 of the curtain 3^a. Referring to Fig. 7 it will be noted that the rod 13 of the curtain 3^a is provided with eye- 20 let members extending back over the curtain to provide an opening for the reception of the hook end. The roller 3 is placed in its operative position immediately below the shaft 5 and the chain 11 and as 25 the structure is actuated the hook members 12 engage the rod 13 and carry the curtain upwardly against the force of a torsional spring within the roller 3. The shaft 5 is provided with a roller or drum member 5^a 30 rigidly keyed thereto which has a diameter as great or greater than the diameter of the sprocket wheels from the ends of the sprocket teeth. The purpose of this member 5^a will be obvious when it is understood that 35 the curtain structure is assisted in its movement by the frictional contact of the roller 5^a and further from the fact that its large diameter prevents the curtain 3^a from having a wearing engagement with the sprocket 10. 40

Each sprocket chain 11 is provided with a stud block 14 located a little above the hook members 12. These stud blocks receive and carry the screw members 15 which support a display rack device 16 which has a number of openings for the reception of the time cards for indicating the time of the departure of trains. Referring to Fig. 5 it will be noted that the device 16 has a sliding 45 engagement with the screw member 15. It will be noted that the movement of the device 16 when lowered by the chains 11 is limited by a suitable limit stop which may be the shafts 7 and 7^a as shown in the figure 50 indicated. As the hook member carrying the rod 13 moves upward initially the end of the hook engages with the lower end of the device 16 and thus prevents the escape of the rod 13 from the hook. As just indicated on the reverse movement of the chain and hook the effect of the limit stop is to permit the hook to leave the device 16 and travel downward and underneath the shaft 5 to a position where the rod 13 of the curtain 55 is discharged from the hook. This ad-

ditional movement of the hook to its discharging position is made possible by the sliding engagement and mounting of the display device 16 on the screw member 15 which is carried by the stud block 14 in the 70 chain.

The structure at the top of the indicator for the movement of the curtains bearing the track number data is operated by the attachment of a crank to the stub shaft 17 which 75 is located at a height convenient to the operator. Suitable gearing connections to transmit the power from this stub 17 to the apparatus at the top of the indicator are indicated by the gear 17^a and the gear 17^b and 80 the shaft 17^c.

The details of the apparatus at the top of the structure are not shown in this application, as these features are described and claimed in my application Serial No. 97,615 85 of which this application is a divisional case.

From the foregoing it will be obvious that a simple and inexpensive indicating device is provided which will correctly and uniformly present the data required. The co-operation of the moving parts makes it possible to lower the device bearing the time cards and thus to co-operate with the apparatus for displaying the station data to effectively prevent the detachment of the apparatus bearing the station data during either the upward or downward movement of the same. 90 95

Changes in shape, location of the parts and material may be made without departing 100 from the scope of the invention.

What I claim is:—

1. A changeable indicator comprising a supporting frame, bearing members adjacent the top of said frame, bearing members adjacent the lower end of said frame, sprockets mounted in conjunction with said bearing members, hook carrying chains on said sprockets, a display curtain adapted for engagement with said hooks of said carrying chains, a display device carried on said chains and spaced above and in operative engagement with the ends of said hooks on said chains, said display device having a sliding relation with respect to said chains 105 whereby the ends of said hooks may engage said display device during the vertical movement of said chains to prevent the escape of said display curtain from said hooks. 110 115

2. A changeable indicator comprising a 120 supporting frame, bearing members adjacent the top of said frame, bearing members adjacent the lower end of said frame, sprockets mounted in conjunction with said bearing members, chains carried on said sprockets, 125 hooks carried by said chains, a display curtain adapted for engagement with said hooks, stud blocks carried by said chains above said hooks, a display device carried on said stud blocks and having a sliding en- 130

gagement therewith, said display device being spaced above and in operative engagement with the ends of said hooks whereby the escape of said display curtain from said 5 hooks is prevented during the vertical movement of said chains.

3. In a changeable indicator, a frame, bearing members at the top and bottom of said frame, sprockets mounted in conjunction with said bearing members, hook carrying chains on said sprockets, a display curtain adapted for engagement with said hook carrying chains, and friction rollers mounted to turn with said sprocket members to engage 10 said display curtain and assist in moving the same, said friction rollers having a diameter at least as great as the diameter of said sprocket members.

4. In a changeable indicator, a frame having upper and lower bearing members, a first rotatable support member mounted in conjunction with said upper bearing member, a second rotatable support member mounted in conjunction with said lower bearing member, a flexible supporting member connecting said rotatable members, means for moving said flexible supporting member up and down, a hook carried by said flexible supporting member, a display curtain adapted 25

for engagement with said hooks, a display device carried on said flexible supporting member and spaced above and in operative engagement with the ends of said hooks on said flexible supporting member, said display device being movably mounted with respect 30 to said flexible support member, whereby the ends of said hooks may engage said display device during the vertical movement of said flexible support member to prevent the escape of said display curtain from said hooks. 35

5. A changeable indicator comprising a supporting frame, upper and lower bearing members mounted on said frame, sprocket members mounted in conjunction with said bearing members, hook carrying chains on 40 said sprocket members, a display curtain adapted to receive said hooks carried by said carrying chains, a display device positioned for elevation by said hooks, and power means to operate said chains to lift said 45 hooks, said hooks being adapted to pick up the end of said curtain in their travel and to continue and pick up the display device to elevate the same with the curtain.

In testimony whereof I have hereunto set 50 my hand.

JOB HUTCHINSON.
